Primary Examiner — Rosemary K Tarcza*Assistant Examiner* — Seth David Kumpf(74) *Attorney, Agent, or Firm* — Andrew C. Cheng(57) **CLAIM**

The ornamental design for a charging station as shown and described.

DESCRIPTION

FIG. 1 is a front, right and top perspective view of a charging station showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of encircled portion 9 of FIG. 1;

FIG. 10 is an enlarged view of encircled portion 10 of FIG. 1; and,

FIG. 11 is an enlarged view of encircled portion 11 of FIG. 2.

The broken lines which depict portions of the charging station form no part of the claimed design. The broken lines which represent boundaries of the enlarged views form no part of the claimed design.
